UNITED STATES PATENT OFFICE.

JOHN W. McMILLAN, OF CHICAGO, ILLINOIS.

DESIGN FOR A VALVE-CASING.

SPECIFICATION forming part of Design No. 33,746, dated December 18, 1900.

Application filed November 23, 1900. Serial No. 37,548. Term of patent 14 years.

To all whom it may concern:

Be it known that I, JOHN W. McMILLAN, a citizen of the United States, residing at Chicago, in the county of Cook and State of Illinois, have invented and produced a new and original Design for Valve-Casings, of which the following is a specification.

In the accompanying drawings, illustrating my design, Figure 1 is a side elevation of a valve-casing, showing my design. Fig. 2 is an end view of the same, and Fig. 3 is a plan view.

As shown in the drawings, the leading or material features of my design consist in a valve-casing having an upper tubular portion A, and a somewhat spherical body portion B, with a depending rectangular portion C. The

lower rectangular portion as seen in side elevation is offset from the axis of the tubular and body portions and as seen in end elevation is somewhat narrower than the body portion. 20

Having described my invention, what I claim as new, and desire to secure by Letters Patent, is—

The design for a valve-casing, substantially as herein shown and described.

In testimony whereof I have signed my name to this specification in the presence of two subscribing witnesses.

JOHN W. McMILLAN.

Witnesses:

S. WRIGHT,
G. S. NOBLE.
